UNITED STATES PATENT OFFICE.

HARRY T. PETERS, OF WOODLAND, PENNSYLVANIA.

SHAVING-CASE.

SPECIFICATION forming part of Letters Patent No. 483,579, dated October 4, 1892.

Application filed May 11, 1892. Serial No. 432,626. (No model.)

To all whom it may concern:

Be it known that I, HARRY T. PETERS, a citizen of the United States, residing at Woodland, in the county of Clearfield and State of Pennsylvania, have invented a new and useful Shaving-Case, of which the following is a specification.

This invention relates to improvements in shaving-cases; and it consists in the construction and arrangement of the parts thereof, as will be more fully hereinafter described and claimed.

The object of this invention is to provide a device of the character set forth embodying all the attachments and compartments necessary for use in shaving and wherein the parts are simple and effective in their construction and operation and comparatively inexpensive in manufacture.

In the drawings, Figure 1 is a perspective view of the improved case, showing the lid open and the hone attachment let down in operative position. Fig. 2 is a transverse vertical section on the line $\alpha\alpha$, Fig. 1. Fig. 3 is a transverse vertical section on the line yy , Fig. 1.

Similar numerals of reference indicate corresponding parts in the several views.

Referring to the drawings, the numeral 1 designates the box or case, having a hinged lid 2, with a looking-glass or mirror 3 embedded in the inner side thereof. Within the box or case are transverse partitions 4, arranged parallel and extending entirely across the same. Between said partitions 4 and fixed to the rear side of the box or case is a narrow partition 5, dividing the rear portion of the said box or case at this point into two compartments 6 and 7. In front of the said partition 5 and considerably below the level of the upper edges of the partitions 4, is a horizontal partition 8 with an opening 9 therein. The said opening 9 is adapted to receive the shaving-mug, and the openings 6 and 7 receive, respectively, bottles containing suitable fluids, such as bay rum and hair-oil.

Between the partitions 4 and the ends of the box or case are secured horizontal partitions 10 and 11, forming receptacles for razors and a comb and brush. Under the partition 10 are arranged two automatically-op-

erating strops 12 and 13, which are superposed one above the other. The strop 12 is coarser than the strop 13, for a purpose which will be readily understood, and the said strops have 55 movement through slots 14 in the front of the box or casing and are provided with metallic stop or limiting plates 15, to which are attached knobs or operating-handles 16.

In the lower portion of the opposite side of 60 the front part of the box or case is situated a drawer 17, adapted to receive shaving-paper, and having a stop-pin 18 in the rear of the same to prevent entire withdrawal of the said drawer from the opening in which it moves. 65

The central upper portion of the front side of the box or case is constructed with a hinged strip 19, having fixed to the inner side thereof a hone 20 and bars or catches 21, which are adapted to be turned outward and engage 70 slots or recesses 22 in the upper edges of the partitions 4 to thereby lock the said hinged strip in closed position. Beneath the lower edge of the said hinged strip 19 an opening 23 is formed in the case in which is mounted 75 a sliding bar 24, having an operating knob or handle 25 and a recess 26 in the upper side thereof to form a front shoulder 27, adapted to abut against a depending projection 28 when moved inward, extending across the 80 upper portion of the opening 23, to thereby limit the inward movement of the said sliding bar 24. The said bar 24 is also provided with a depending pin 28^X, adapted to strike a cross-piece 29^X against the lower inner portion of the front of the box. This bar 24 forms 85 a rest or support for the hinged strip 19 when the latter is let down for the purpose of using the hone carried on the inner side thereof.

The ends of the box or case 1 are provided 90 with hooks 29 for attaching the same to a wall or other support, if so desired, or the device as an entirety may be placed on a stand or table. A further attachment consists of a spring 30, which is connected to the lid or 95 cover 2 and the box or case, to prevent the said lid from readily falling down when open.

The box or case herein described is neat and compact in form and provides means for storing the several tools and appliances necessary for use in shaving. If desired, the said box or case may be suitably ornamented or

artistically embellished with pleasing designs and may also be constructed of different kinds of wood or other material.

A suitable lock and key will be applied in connection with the box or case, whereby the same may be securely fastened to prevent entrance thereinto, if so desired.

Having thus described the invention, what is claimed as new is—

10. In a device of the character set forth, the combination of a box or case having transverse partitions vertically disposed intermediate of the ends thereof and extending completely from front to rear to form a central space, the front side of said box or case being cut away to form an opening in line with the said central space, a horizontal partition between and below the said transverse partitions, extending to within a short distance of the back side of the box or case and having a circular opening therein adjacent to one of said transverse partitions to receive a shaving-mug, a rear vertically-disposed narrow partition arranged between the central

portion of the rear edge of said horizontal partition and the back side of the box to form receptacles for removably receiving bottles, shallow receptacles between the said transverse partitions and the ends of the box or case, razor-strops at one side of said box or case, a drawer at the lower portion of the opposite side of said box or case, a strip hinged to the bottom wall of the opening in the front side of the box or case, a hone carried on the inner side of said strip, catches secured to the upper portion of the inner side of said strip, an adjustable bar below said strip to form a support for the same, and a hinged lid or cover having a mirror on the inner side thereof, substantially as described.

25. In testimony that I claim the foregoing as my own I have hereto affixed my signature in the presence of two witnesses.

HARRY T. PETERS.
